UNITED STATES PATENT OFFICE.

FRANCIS WAYLAND, OF SALEM, MASSACHUSETTS.

HIDE AND LEATHER WORKING MACHINE.

1,131,756.

Specification of Letters Patent. Patented Mar. 16, 1915.

Application filed March 14, 1912. Serial No. 683,912.

To all whom it may concern:

Be it known that I, FRANCIS WAYLAND, a citizen of the United States, and resident of Salem, in the county of Essex and State of Massachusetts, have invented new and useful Improvements in Hide and Leather Working Machines, of which the following is a specification.

This invention relates to a machine for treating skins, hides and leather, and particularly for glazing and at the same time stretching and staking.

The principal objects of the invention are to provide a machine of novel and improved construction and operation which will glaze skins over their whole extent at one time, at the same time soften the skin and especially the grain surface of the skin, and stretch and stake the skin preparatory to the glazing and deliver it in stretched condition to the action of the glazing devices.

According to the glazing and burnishing methods heretofore generally employed, the skin has been laid upon a table or supporting bed, stretched out as flat as possible by hand, and glazed with a "glass." It is necessary to use a narrow glass and to treat only a narrow area of the skin at each stroke in order to get the best results, and to properly soften and work the grain surface, since if a wide glass is used and a wide area of the skin is treated at one time thereby, the glass tends to lay down and harden the surface. With my invention the skin is subjected to the action of a work roll or glazing roll provided with a plurality of glazing projections, said roll treating the whole extent of the skin at once and yet without the hardening effect of a wide glass, since the glazing projections each engage only a narrow part of the skin at one time, thus properly working and softening the skin. Furthermore, my glazing projections also perform stretching, staking and putting out functions. Mechanism is also provided to stretch the skin preparatory to the glazing and to pass the skin in stretched condition and under tension to the glazing roll, to prevent wrinkling or pleating of the skin in the glazing operation. Such mechanism will also perform the operations of staking, putting out, unhairing, etc.

In the accompanying drawings, which illustrate one embodiment of the invention,—Figure 1 is a side or end elevation of a leather working machine embodying my invention; Fig. 2 is a sectional view showing the relation between the rolls and the stretching jaws hereinafter described, parts being broken away; Fig. 3 is a fragmentary front view showing a preferred arrangement of the glazing projections of the work roll; Fig. 4 is a fragmentary face view of one of said jaws; and Fig. 5 is a fragmentary face view of the other of said jaws.

Referring to the drawings: A represents the work roll, B the bed roll against which the skin lies and by which it is supported while being acted upon by the work roll, and C is a pinch or feed roll, the rolls B and C acting together to feed or draw the skin S through the machine.

The work roll A is driven by a pulley A'; the pinch roll or feed roll C is independently driven by any suitable power mechanism; and the bed roll B is driven from roll C by gears c and b mounted respectively on the shafts carrying rolls C and B. The work roll A is journaled on the frame F of the machine, and the bed roll B is journaled on swinging arm E, which is pivoted to the frame at D and constitutes a movable carrier for said bed roll, whereby the rolls A and B may be separated to admit the work, and brought together to engage the work. The roll C is journaled at its ends in blocks c' mounted at each end of the frame to slide in ways c². A spring c³ normally presses each block c', and the roll C carried thereby, in the direction of the bed roll B.

The surface of the work roll A is provided with glazing projections which may be of any form and of any material adapted to glaze or burnish the skin. These glazing projections preferably comprise two diverging sets of helical ribs or vanes a, made of glass, hardened wood fiber composition, or other suitable material. They have smooth working surfaces and by reason of their diverging or helical arrangement not only glaze and burnish the skin, but also perform stretching, putting out and staking functions. In addition to the ribs a, other glazing projections may be provided such

as the smooth rounded knobs a' of similar material arranged between the ribs a . Or such knob-like projections could be used without the ribs. Roll A is covered with an 5 elastic cushion a^2 of felt or other suitable springy material, and the glazing projections are secured to and bear on this cushion so that said projections will yield inwardly and provide yielding pressure of the glazing 10 projections upon the work lying against the bed roll B, when the machine is in operation. The ribs a are secured to the cushion a^2 by angle clamps a^3 .

Below and close to the rolls A and B are 15 a pair of stretching jaws G and H of substantially the same length as said rolls. One of said jaws, the jaw H as herein shown, is rigidly mounted on the swinging arm E, and the other, the jaw G, is pivotally mounted on said frame at I. Each of 20 said jaws is provided with two diverging sets of vanes or blades, one set inclined to the right and the other to the left, the blades of one jaw intermeshing with those 25 of the other when the jaws are closed in operative position, that is, the blades of one jaw projecting into the channels between the blades of the other, as shown in Figs. 1 and 2. The blades of jaw G are 30 shown at g and those of jaw H are shown at h . The blades of one or the other of said jaws, and as herein shown the blades g of jaw G, are comparatively thin and are flexible and resilient, to provide for inequalities in 35 the thickness of the skin, so that the latter will be treated uniformly throughout its whole surface, while the blades h of the other jaw are rigid and inflexible. One of 40 said jaws also has two longitudinally extending scraper bars h' , h' , one at each side of said blades, to press and scrape part of the moisture or water out of the skin as it passes between the jaws, and the other jaw has a pair of opposed pads of felt, or other 45 suitable material, with which said scraper bars coöperate to press and scrape the skin. Said bars h' also serve as tension bars, the lower bar h' putting tension on the skin for the action of blades g , and both bars serving 50 to put tension on the skin for the action of the glazing roll. The pressure upon the skin between the sides of said blades may be varied by means of the pedal P, acting through connecting rod J, and pressed 55 down by the foot of the user to increase the pressure between said blades, and lifted by spring K to relieve said pressure.

The operation of the machine is as follows: The arms E, carrying the bed roll B 60 and jaw H, are swung away from work roll A and feed roll C, thus opening the parts which coact upon the skin, to admit of the insertion of the skin. The mechanism for swinging the arms E back and forth may 65 be of any well known construction and mode

of operation employed in other leather working machines, and need not here be described. The skin S is then placed between the jaws G and H, the roll A and bed roll B, and the rolls C and B, and the arms 70 E swung to closed position, said jaws and rolls engaging the skin as shown in Fig. 2. Thereupon, the rolls being rotated in the directions shown by the several arrows, rolls C and B will feed or draw the skin 75 upward and outward from the machine, and the glazing projections on roll A will glaze and burnish the surface of the skin lying against bed roll B. By reason of the diverging helical form of the projections a , 80 roll A will also perform spreading, stretching, staking and putting out functions. The jaws G and H, by their diverging blades or vanes, and bars, stretch the skin laterally preparatory to passing it to the work roll; 85 perform staking and putting out operations; press and scrape off part of the water from the skin which comes wet from the previous steps in its treatment; deliver the skin in stretched and flat condition to the 90 glazing roll; and also place longitudinal tension on the skin, which tension may be varied by pedal P, to regulate the action on the skin of the blades of said jaws and of the projections of said glazing and putting 95 out roll.

I claim:

1. In a machine of the character described, a bed, a work roll provided with glazing projections made of a form and material 100 adapted to glaze or burnish a skin, a pair of stretching jaws one at least of said jaws having two diverging sets of blades coöperating with the other jaw to engage and stretch the skin laterally before it passes to 105 said roll, and means to vary the pressure between said jaws.

2. In a machine of the character described, a bed, a work roll provided with glazing projections made of a form and material adapted to glaze or burnish a skin, a pair of 110 stretching jaws each having two diverging sets of blades, the blades of one jaw intermeshing with those of the other to engage and stretch the skin laterally before it passes 115 to said roll, and means to vary the pressure between the sides of said blades.

3. In a machine of the character described, a bed, a work roll provided with glazing projections made of a form and material adapted to glaze or burnish a skin, and a pair of stretching jaws one at least of said jaws having two diverging sets of blades coöperating with the other jaw to engage and stretch the skin laterally before it passes to 120 said roll, said blades being resilient.

4. In a machine of the character described, a bed, a work roll provided with glazing projections made of a form and material adapted to glaze or burnish a skin, 125

- and a pair of stretching jaws one at least of said jaws having two diverging sets of blades coöperating with the other jaw to engage and stretch the skin laterally before it passes to said roll, and one of said jaws having a longitudinally extending scraper bar adapted to press and scrape moisture from the skin.
5. In a machine of the character described, 10 a bed, a work roll provided with glazing projections made of a form and material adapted to glaze or burnish a skin, and a pair of stretching jaws one at least of said jaws having two diverging sets of blades co- 15 operating with the other jaw to engage and stretch the skin laterally before it passes to said roll, one of said jaws having a longitudinally extending scraper bar, and the other jaw a longitudinally extending pad, 20 said scraper bar and pad coöperating to press and scrape moisture from the skin.
6. In a machine of the character described, 25 a bed, a work roll provided with glazing projections made of a form and material adapted to glaze or burnish a skin, and a pair of stretching jaws one at least of said jaws having two diverging sets of blades coöperating with the other jaw to engage and stretch the skin laterally before it passes 30 to said roll, and one of said jaws having two longitudinally extending scraper bars located on opposite sides of said sets of blades, adapted to press and scrape moisture from the skin.
- 35 7. In a machine of the character described, a bed, a work roll provided with glazing projections made of a form and material adapted to glaze or burnish a skin, and a pair of stretching jaws each having two diverging sets of blades, the blades of one jaw intermeshing with those of the other to engage and stretch the skin laterally before it passes to said roll, one of said jaws also having two longitudinally extending scraper 40 bars located on opposite sides of the blades, and the other of said jaws having two longitudinally extending pads, said scraper bars and pads coöperating to press and scrape moisture from the skin.
- 50 8. In a machine of the character described, a pair of jaws each provided with diverging blades, and one at least of said jaws also being provided with a tension and scraper bar.
9. In a machine of the character described, 55 feed rolls by which the skin is drawn through the machine, and a pair of stretching jaws, one at least of which has two diverging sets of blades, said jaws being adapted simultaneously to engage opposite sides of a skin drawn therebetween by said feed rolls, and to straighten and stretch the skin laterally before it passes to said feed rolls and to pass said skin in such straightened and stretched condition and under longitudinal tension to said rolls.
10. In a machine of the character described, 70 feed rolls by which the skin is drawn through the machine, and a pair of stretching jaws, one at least of which has two diverging sets of blades, said jaws being adapted simultaneously to engage opposite sides of a skin drawn therebetween by said feed rolls, and to straighten and stretch the skin laterally before it passes to said feed rolls and to pass said skin in such straightened and stretched condition and under longitudinal tension to said rolls, and means to vary the pressure between said stretching jaws.
11. In a machine of the character described, 75 feed rolls by which the skin is drawn through the machine, and a pair of stretching jaws, one at least of which has two diverging sets of blades, said blades being resilient, said jaws being adapted simultaneously to engage opposite sides of a skin drawn therebetween by said feed rolls, and to straighten and stretch the skin laterally before it passes to said feed rolls and to pass said skin in such straightened and stretched condition and under longitudinal tension to said rolls.
12. In a machine of the character described, 80 feed rolls by which the skin is drawn through the machine, and a pair of stretching jaws, each jaw having diverging sets of blades, the blades of one jaw intermeshing with the blades of the other jaw, said jaws being adapted simultaneously to engage opposite sides of a skin drawn therebetween by said feed rolls and to straighten and stretch the skin laterally before it passes to said feed rolls and to pass said skin in such straightened and stretched condition and under longitudinal tension to said rolls.
13. In a machine of the class described, 85 in combination, a substantially flat table provided with a plurality of blades, a second substantially flat table provided with a plurality of blades arranged to coöperate with the blades on the first mentioned table and to overlap the same, means to move one of said tables toward and from the other to cause a hide or skin supported by one of said tables to have its opposite surfaces simultaneously engaged by said blades, means to draw the hide or skin between said blades 90 in an irregular path, and means to move one of said tables in a plane substantially parallel with the other of said tables to vary the distance between the overlapping blades of each set or pair of blades.
14. In a machine of the class described, 95 in combination, two substantially flat tables provided on their contiguous faces with a plurality of sets of blades arranged to overlap in their working position, means for 100

moving one of said tables toward and from the other to enable a hide or skin to be placed between the blades on the said tables, and means to move one of the said tables in 5 a plane substantially parallel with the other table when the said tables are in their working position to vary the distance between the overlapping blades and thereby vary the

pressure of the blades on the interposed hide or skin, substantially as described.

Signed by me at Boston, Massachusetts, this ninth day of March 1912.

FRANCIS WAYLAND.
